(57) **CLAIM**

The ornamental design for a folding colander, as shown and described.

DESCRIPTION

FIG. 1 is a perspective view of the colander showing my new design, the broken lines are for illustrative purposes only and form no part of the claimed design;

FIG. 2 is a left side view thereof, the opposite side being a mirror image;

FIG. 3 is a front view thereof, the opposite side being a mirror image; and,

FIG. 4 is a top plan view thereof.
